UNITED STATES PATENT OFFICE.

EMIL W. SOMMER, OF GLENDALE, WEST VIRGINIA.

HEADLIGHT.

Application filed March 27, 1922. Serial No. 547,120.

To all whom it may concern:

Be it known that I, EMIL W. SOMMER, a citizen of the United States of America, and resident of Glendale, county of Marshall, 5 and State of West Virginia, have invented certain new and useful Improvements in Headlights, of which the following is a specification.

This invention relates broadly to headlights of the general type commonly employed on motor vehicles, and it has for its primary object to provide a headlight in which the lamp is at all times concealed from view, thus effectually eliminating the blinding effect which is incident to exposure of the brilliantly glowing lamp filament within the range of vision of persons approaching the headlight.

A further object is to provide a headlight 20 by means of which the rays of light emanating from the lamp are projected forward at a slight downwardly inclination for illuminating the roadway and for preventing the obtrusive glare of headlights as heretofore 25 commonly constructed.

With these and other objects in view, the invention resides in the features of construction and arrangement of parts which will hereinafter be described, reference being had 30 to the accompanying drawings, in which—

Figure 1 is a front elevation of a headlight constructed in accordance with my invention;

Figure 2 is a central vertical section of the 35 same; and—

Figure 3 is a section on line 3—3, Fig. 2.

Referring to said drawings, 1 indicates a lamp casing of an ordinary parabolic form, within the rear part of which is fitted in an 40 approximately upright position a flat, or substantially flat, circular reflecting element, preferably a glass mirror 2. Mounted upon and occupying a position in front of the upper portion of the casing is a supplementary casing 3 which, viewed in front elevation, is of crescent form and which is approximately semi-cylindrical in central cross section, as shown in Fig. 2.

Disposed centrally within the casing 3 to 50 face downward and rearward at an angle of about 45° is a stationary parabolic reflector 4 of relatively small size to which a lamp 5 is fitted in such manner that the major portion of the direct rays therefrom and the 55 rays reflected by said reflector will be di-

rected against the reflecting elements 2 of the main casing.

The upper rear edge of the supplementary casing 3 is shaped to form a rim 6 for seating upon the adjacent portion of the rim 7 of the main casing, and supplementing said rim 6 is a ring-like downward extension 6^a for embracing the portion of the main-casing rim 7 located below the casing 3, whereby the latter is detachably and rigidly mounted 65 upon said main casing.

The conductor wires which lead to the lamp 5 are preferably directed through a passage formed by a channel member 8 which is rigidly attached to the lamp casing 1, leading from the rear part of said casing to and over the rim 7 of the latter. A corresponding bow or hump 6^b formed in the rim 6 of the supplementary casing allows for the fitting of the latter over the 75 adjacent end of said channel member.

Hinged centrally upon an inclined flange 9 formed upon the forwardly bowed lower edge portion of the supplementary casing is the similarly bowed upper portion of a 80 frame 10 which has its lower portion disposed vertically for seating against the front of the main casing and which is detachably held in rigid relation to the latter, as by a suitably spring catch 11. Said frame 10 has mounted therein a glass face 12 of arcuately-curved form in horizontal section, through which pass the light rays reflected forward by the mirror or other reflecting element 2, said frame and glass 90 together constituting a door which permits of convenient access to the interior of the headlight.

What is claimed is—

1. A headlight comprising a main casing 95 having a vertically disposed open front end, a reflecting element located within the rear part of said casing, a supplementary casing of concavo-convex form in central section located forward of said casing and mounted upon the upper part of the latter and facing rearwardly, a lamp located interiorly of said supplementary casing, a reflector embracing said lamp and disposed to concentrate rays from the latter upon said reflecting element, and a hinged door embodying a glass face disposed in closing relation to the front of said main casing below said supplementary casing, the upper edge of said door being arcuately curved to 110

conform to the lower edge of said supplementary casing and being hinged to said lower edge.

2. A headlight comprising a main casing having a vertically disposed open front end, a reflecting element located within the rear part of said casing, a casing of concavo-convex form in central section supplementary to the main casing, said supplementary casing being mounted upon the upper part of said main casing and facing rearwardly, said supplementary casing having a rim which is extended in ring-like form for seating upon the front edge portion of said main casing, a lamp located behind said supplementary casing, a reflector embracing said lamp and disposed to concentrate the rays from the latter upon said reflecting element, a door frame shaped to conform to the under side of said supplementary casing and that portion of the main casing below said supplementary casing, and a glass face fitted in said frame, said glass face being arcuately curved in horizontal section.
3. A headlight comprising a main casing having a vertically disposed open front end, a reflecting element located within the rear

part of said casing, a casing supplementary to the main casing, said supplementary casing being of concavo-convex form in central section and being mounted upon the upper part of said main casing and facing rearwardly, said supplementary casing having a rim which is extended in ring-like form for embracing said open front of the main casing and having an arcuately curved lower edge, a lamp located interiorly of said supplementary casing, a reflector located adjacent to and forward of said main casing and disposed for concentrating rays from the lamp upon the aforesaid reflecting element, a door frame hinged to the lower central curved edge portion of said supplementary casing, said frame being shaped to conform to said edge portion and to the main casing below said supplementary casing, and a glass face carried by said frame.

In testimony whereof, I affix my signature in presence of two subscribing witnesses.

EMIL W. SOMMER.
